UNITED STATES PATENT OFFICE.

FRANCIS LATTIMER, OF RICHMOND, NOVA SCOTIA, CANADA, ASSIGNOR OF TEN TWENTY-FOURTHS TO JOHN AHERN, OF SAME PLACE, AND WM. H. BATES, ALEXANDER CARTER, ARTHUR SMITH, WILLIAM F. LINTON, WILLIAM McCULLY, SEYMOUR E. GOURLEY, AND LYMAN J. WALKER, OF TRURO, CANADA.

KNOB ATTACHMENT.

SPECIFICATION forming part of Letters Patent No. 290,247, dated December 18, 1883.

Application filed February 13, 1883. (Model.)

To all whom it may concern:

Be it known that I, FRANCIS LATTIMER, of Richmond, in the county of Halifax, Province of Nova Scotia, and Dominion of Canada, have invented a new and useful Improvement 5 in Knob-Spindle Fastenings for Mortise-Locks, of which the following is a full, clear, and exact description.

Reference is to be had to the accompanying drawing, forming a part of this specification, and which is a sectional elevation of my improvement.

The object of this invention is to facilitate the adjustment of knobs to doors of different thicknesses.

The invention consists in the combination, with the knob and its shank, of an interior bolt having an exterior screw-thread and a spindle-receiving socket at its projecting end, 20 and the extension-shank having interior screw-thread and a spindle-receiving aperture, whereby the said knob can be readily adjusted to the thickness of the door, as will be hereinafter fully described.

25 A represents a door, in which is formed a mortise, B, to receive a lock.

C is the knob, the inner end of the shank D of which fits into a deep rabbet, E, formed in the face of the rose F. The shank D receives the bolt G, upon which it and the knob are molded or cast, or to which the said shank is secured by rivets or other suitable means.

The bolt G has a screw-thread, H, formed upon the outer surface of its end, which projects beyond the end of the shank D, and has a square socket, I, formed in it to receive the end of the spindle J, which passes through the door A and the lock. The inner surface of the shank D has a rabbet, K, formed in it, 40 to fit upon the outer end of the extension shank L, which has a corresponding rabbet, M, formed in its outer surface.

The extension-shank L has a countersink, N, formed in its outer end, to receive the end of the bolt G, and has a screw-thread, O, formed in the surface of the said countersink, to receive and fit upon the screw-thread H of the bolt G.

The extension-shank L has a square hole, P, formed through its center in line with the center of the countersink N, to correspond 50 with the socket I of the bolt G, so that the spindle J will pass through the hole P and enter the socket I, and will lock the said bolt G and extension-shank L together and prevent them from turning upon each other after the 55 said spindle J has been inserted.

Around the inner end of the extension-shank L is formed an annular groove, Q, to receive the open slotted plate R, which is inserted at the side of the lock in a recess in 60 the door A, at the side of the mortise B, to lock the knob C in place upon the spindle J.

In fitting the knobs to doors the extension-shanks L are inserted in place, and the bolts G of the knobs C are screwed into the said 65 extension-shanks L to such a depth as the thickness of the door A may render necessary. The knobs C and extension-shanks are then removed, the spindle J is passed through the door and lock, the knobs C and extension-shanks L are placed upon the ends of the 70 spindle J and returned to their places, and the locking-plate R is inserted in its place, making all secure.

With this construction no washers need be 75 used between the knob-shank D and the rose F in adjusting the knobs C to the thickness of doors.

Having thus described my invention, I claim as new and desire to secure by Letters Patent— 80

The combination, with the knob C and shank D, of the bolt G, having exterior screw-thread, H, and spindle-receiving socket I, the extension-shank L, having interior screw-thread, O, and spindle-receiving aperture P, and means 85 for securing the extension-shank to the door, substantially as herein shown and described, whereby the knobs can be readily adjusted to doors of different thicknesses, as set forth.

FRANCIS LATTIMER.
